[57] CLAIM

The ornamental design for compact, as shown and described.

DESCRIPTION

FIG. 1 is a perspective view of the compact embodying the new design;
 FIG. 2 is a top plan view thereof;
 FIG. 3 is a bottom plan view thereof;
 FIG. 4 is a front elevational view thereof;
 FIG. 5 is a rear elevational view thereof; and,
 FIG. 6 is a left side elevational view thereof, the right side elevational view being the mirror image thereof.
